CLAIM

I claim the ornamental design for a table tennis table, as shown and described.

DESCRIPTION

FIG. 1 is a first side elevation view of an embodiment of a table tennis table of our new design;

FIG. 2 is a second side elevation view of the table tennis table of FIG. 1;

FIG. 3 is a bottom plan view of the table tennis table of FIG. 1;

FIG. 4 is a top plan view of the table tennis table of FIG. 1;

FIG. 5 is a front elevation view of the table tennis table of FIG. 1;

FIG. 6 is a rear elevation view of the table tennis table of FIG. 1; and,

FIG. 7 is a side perspective of the table tennis table of FIG. 1.

The broken lines showing of fasteners located on the bottom side of the table is for the purpose of illustrating portions of the table and form no part of the claimed design.
